(57) **CLAIM**

The ornamental design for a gazebo, as shown and described.

DESCRIPTION

FIG. 1 is an elevated perspective corner view of the gazebo of the present design;

FIG. 2 is a side plan view of the gazebo of the present design; the opposite and adjacent side views being identical thereto; FIG. 3 is a top plan view of the gazebo of the present design; FIG. 4 is a bottom plan view of the gazebo of the present design; and,

FIG. 5 is a front perspective side view of the gazebo of the present design.

The broken lines depict portions of the gazebo that form no part of the claimed design.
